CLAIM

The ornamental design for a support for computer terminals, as shown and described.

DESCRIPTION

FIG. 1 is a top, left and front perspective view of a support for computer terminals showing my new design;

FIG. 2 is another top, left and front perspective view thereof showing the support for computer terminals in an extended position;

FIG. 3 is a bottom, right and rear perspective view of the support for computer terminals thereof, but in the non-extended position;

FIG. 4 is front view thereof;

FIG. 5 is back view thereof;

FIG. 6 is a left-side view thereof;

FIG. 7 is a right-side view thereof;

FIG. 8 is a top view thereof; and,

FIG. 9 is a bottom view thereof.

The broken lines in the drawings depict portions of the support for computer terminals that form no part of the claimed design.
